(57) **CLAIM**

We claim the ornamental design for an electronic device shell, as shown and described.

DESCRIPTION

FIG. 1 is a front perspective view of an electronic device shell; FIG. 2 is a front elevational view of the electronic device shell;

FIG. 3 is a back elevational view thereof;
FIG. 4 is a left elevational view thereof;
FIG. 5 is a right elevational view thereof;
FIG. 6 is a top plan view thereof; and,
FIG. 7 is a bottom plan view thereof.
